UNITED STATES PATENT OFFICE.

HENRY M. PAULSEN, OF LONG BEACH, CALIFORNIA, ASSIGNOR TO DUNN MANUFACTURING COMPANY, OF OXNARD, CALIFORNIA, A CORPORATION OF CALIFORNIA.

WELL ELEVATOR.

Application filed September 12, 1923. Serial No. 662,182.

This invention relates to elevators, such as used for lifting casing and other objects, and the said invention has for an object an elevator adapted to insure that the work is properly embraced by the elevator prior to load being imposed upon such elevator.

Further object is the provision of an elevator which is novel in structure, simple to manufacture, economical as to repairs, and fool proof and positive in its action.

With the above and other objects in view, the invention consists in the novel, and useful provision, formation, construction, association, and relative arrangement, of parts, members and features, all as shown in a certain embodiment in the accompanying drawing, described generally, and more particularly set forth in the appended claims.

In the drawing:

Figure 1 is a side view of the improved elevator, with casing shown in dotted lines;

Figure 2 is a top plan view of the elevator shown in Figure 1;

Figure 3 is a cross sectional view on the line 3-3 of Figure 2 and looking in the direction of the appended arrows;

Figure 4 is a fragmentary cross sectional view on an enlarged scale, with the said view taken on the line 4-4 of Figure 3 and looking in the direction of the appended arrows; and,

Figure 5 is a fragmentary perspective view, certain parts being in section, with the said view taken on the line 5-5 of Figure 4, and looking in the direction of the appended arrows.

Corresponding parts of all the figures are designated by the same reference characters.

Referring now with particularity to the drawing, the elevator is designated as an entirety and in one embodiment by A, and said elevator includes a body member a and a gate member b hingedly associated with the body. In the showing the body member a is provided with two diametric extensions 1 and 2, which extensions are adapted to cooperate with links, a bail, or the like, for the purpose of carrying the said elevator. The said extensions, in the showing, may be curvilinearly recessed, as shown at 3 and 4, thus insuring that the said links or bail shall not be disengaged from the extensions, due to jar or otherwise, when the elevator is in use. In addition, the said body is provided with two diametric extensions 5 and 6,

which are spaced from the extensions 1 and 2, and the extensions 1 and 2 may be provided with lugs 7 and 8, through which lugs and the extensions 5 and 6 are aligned bores 9, 10, 11 and 12. Bolts may be passed through each pair of aligned bores, thereby insuring that the bail will not be disassociated from the extensions 1 and 2 when the elevator is non-load sustaining. As is usual, the body a is formed with a curved portion, as shown at 13, within which curved portion and a curved portion of the gate b, as shown at 14 work is placed to be embraced by the body and the gate when the gate is latched closed, as shown in Figures 1 and 2.

The body a is provided with an inset recess, as shown at 15, within which recess is received a nose portion 16 of the gate b when said gate is latched to the body. As is usual, the body a is formed with a curved portion, as shown at 13, within which curved portion and a curved portion of the gate b, as shown at 14 work is placed to be embraced by the body and the gate when the gate is latched closed, as shown in Figures 1 and 2.

The body a is provided with an inset recess, as shown at 15, within which recess is received a nose portion 16 of the gate b when said gate is latched to the body. As is usual, the body a is formed with a curved portion, as shown at 13, within which curved portion and a curved portion of the gate b, as shown at 14 work is placed to be embraced by the body and the gate when the gate is latched closed, as shown in Figures 1 and 2.

The body a is provided with an inset recess, as shown at 15, within which recess is received a nose portion 16 of the gate b when said gate is latched to the body. As is usual, the body a is formed with a curved portion, as shown at 13, within which curved portion and a curved portion of the gate b, as shown at 14 work is placed to be embraced by the body and the gate when the gate is latched closed, as shown in Figures 1 and 2.

The body a is provided with an inset recess, as shown at 15, within which recess is received a nose portion 16 of the gate b when said gate is latched to the body. As is usual, the body a is formed with a curved portion, as shown at 13, within which curved portion and a curved portion of the gate b, as shown at 14 work is placed to be embraced by the body and the gate when the gate is latched closed, as shown in Figures 1 and 2.

The body a is provided with an inset recess, as shown at 15, within which recess is received a nose portion 16 of the gate b when said gate is latched to the body. As is usual, the body a is formed with a curved portion, as shown at 13, within which curved portion and a curved portion of the gate b, as shown at 14 work is placed to be embraced by the body and the gate when the gate is latched closed, as shown in Figures 1 and 2.

The body a is provided with an inset recess, as shown at 15, within which recess is received a nose portion 16 of the gate b when said gate is latched to the body. As is usual, the body a is formed with a curved portion, as shown at 13, within which curved portion and a curved portion of the gate b, as shown at 14 work is placed to be embraced by the body and the gate when the gate is latched closed, as shown in Figures 1 and 2.

The body a is provided with an inset recess, as shown at 15, within which recess is received a nose portion 16 of the gate b when said gate is latched to the body. As is usual, the body a is formed with a curved portion, as shown at 13, within which curved portion and a curved portion of the gate b, as shown at 14 work is placed to be embraced by the body and the gate when the gate is latched closed, as shown in Figures 1 and 2.

The body a is provided with an inset recess, as shown at 15, within which recess is received a nose portion 16 of the gate b when said gate is latched to the body. As is usual, the body a is formed with a curved portion, as shown at 13, within which curved portion and a curved portion of the gate b, as shown at 14 work is placed to be embraced by the body and the gate when the gate is latched closed, as shown in Figures 1 and 2.

The body a is provided with an inset recess, as shown at 15, within which recess is received a nose portion 16 of the gate b when said gate is latched to the body. As is usual, the body a is formed with a curved portion, as shown at 13, within which curved portion and a curved portion of the gate b, as shown at 14 work is placed to be embraced by the body and the gate when the gate is latched closed, as shown in Figures 1 and 2.

The body a is provided with an inset recess, as shown at 15, within which recess is received a nose portion 16 of the gate b when said gate is latched to the body. As is usual, the body a is formed with a curved portion, as shown at 13, within which curved portion and a curved portion of the gate b, as shown at 14 work is placed to be embraced by the body and the gate when the gate is latched closed, as shown in Figures 1 and 2.

The body a is provided with an inset recess, as shown at 15, within which recess is received a nose portion 16 of the gate b when said gate is latched to the body. As is usual, the body a is formed with a curved portion, as shown at 13, within which curved portion and a curved portion of the gate b, as shown at 14 work is placed to be embraced by the body and the gate when the gate is latched closed, as shown in Figures 1 and 2.

The body a is provided with an inset recess, as shown at 15, within which recess is received a nose portion 16 of the gate b when said gate is latched to the body. As is usual, the body a is formed with a curved portion, as shown at 13, within which curved portion and a curved portion of the gate b, as shown at 14 work is placed to be embraced by the body and the gate when the gate is latched closed, as shown in Figures 1 and 2.

provided with the cam shaped lug *c* as shown in Figure 3. The body *a* is formed with a curved recess 20, adapted to accommodate the cam member *c* and permit the elevator gate *b* to swing open or closed. The plunger member *d* includes a head 21, joined with a stem 22, at the end of which stem is formed a curved nose 23. The said stem is likewise provided with a longitudinal groove or key-way 24. The body *a* is formed with a recess 25, adapted to accommodate the head 21 when the plunger is in a certain position. The body *a* is formed with bores 26 and 27, adapted to accommodate the stem 22 of the plunger. The bore 27 is of smaller diameter than the bore 26, the said plunger being adapted to have a spring 28 coiled about the same and confined within the bore 26 and bearing at one end against the head 21 and at the other end against the flange 29 included between the two bores 26 and 27. The said body is likewise provided with a lateral screw threaded bore 30, within which is received a screw 31, provided with a part adapted to enter the longitudinal groove or way 24 in the stem of the plunger, the purpose being to prevent rotation of the plunger during movement thereof. The end of such plunger stem, as stated, is formed with a grooved nose 23, and said nose is adapted to cooperate with the periphery of the cam *c*. It will be noted that the cam is segmental in form, and that the face of such cam curves downwardly from the top edge of the knuckle 17, as shown at 32, to the bottom, as shown at 33, partly circumscribing the axis of the hinge. The curved nose of the plunger is adapted to ride on such cam face. The normal position for the parts would be that illustrated in Figure 1 in full lines, with the head 21 of the plunger extending above the top of the elevator. When work is to be imposed upon the elevator, such as for instance the carrying of casing, illustrated at dotted lines in Figure 1 at 34, a collar or coupling 35 carried by the casing will have a portion thereof contact with the head 21. It will be noted that the said head 21 extends as far as the curves 13 and 14 of the body and gate and that the end of such head 21 is curved, as shown at 36. Thus when tubing 34 having the collar or sleeve or coupling 35 is confined within the body *a*, the collar 35 would first contact when the elevator was lifted with the head 21 and tend to force the same downwardly and into the confines of the slot 25 of said body. As the plunger is guided within the bores 26 and 27, the curved nose of such plunger is forced downwardly upon the cam edge of the cam member *c*, and this cams the gate *b* closed, so that the same will embrace a part of the work. It is hence impossible to place any load upon the gate without camming the gate closed to the body member. Upon the releasing of any load from the elevator, the spring member 28 will lift the plunger from the cam edge of the cam and allow the gate to be opened. Latch means *d* is provided for the gate and said means may be conventional in form, consisting of a handle 36 joined with spaced knuckles 37 and 38, which spaced knuckles are on opposite sides of a knuckle 39 carried by the gate *b*, there being a pin adapted to be passed through the said knuckles for holding them in working relation. The knuckles 37 and 38 carry a latch head, shown dotted in Figure 2 at 40, the latch head being adapted to cooperate with a member 41 carried by the body *a*. In this connection it will be seen that the end 16 of the gate is received within the cutaway portion 15 of the body, and that the latch head is so formed as to automatically lock when the gate is swung closed. The latch 85 may be released by pulling upon the handle 36, which would release the latch head 40 from the member 41. However, it is impossible to open the gate while load is imposed upon the elevator, for the reason that the plunger will be depressed and prevent such opening.

In Figure 5 the upper arrow shown at 42 indicates movement of the plunger to close the gate, and the lower arrow 43 of said figure shows the directional movement of the gate during closing operation thereof. Furthermore, the said section 5-5 of Figure 4 and the showing of Figure 5 illustrates the parts revolved to view in the plane of Figure 1. In Figure 4 the gate is being revolved in the direction of the arrow to close the same when the plunger is pushed downwardly.

I have thus provided an elevator which is practical, fool proof in operation, easy of manufacture and with few parts to get out of adjustment.

It is obvious that various changes, modifications and variations may be made in practicing the invention in departure from the particular showing, and that said changes and variations may be made within a fair interpretation of the invention, and as set forth by the scope of the appended claims.

I claim:

1. In an elevator of the character disclosed, a body adapted to be presented to work, and provided with a gate cooperating with the body; of means disposed in position to be engaged and substantially vertically actuated by the weight of the work by the work to which the body is applied to actuate the gate to move the same in a closing direction.
2. In an elevator of the character disclosed, a body adapted to be presented to work, and provided with a gate cooperating with the body; of means disposed in position to be engaged and substantially vertically actuated by the weight of the work by the work to which the body is applied to actuate the gate to move the same in a closing direction.

tion to be engaged and substantially vertically actuated by the weight of the work by the work to which the body is applied to actuate the gate to move the same in a closing direction; said means for actuating the gate serving to retain the same in closing position.

3. In an elevator of the character disclosed, a body adapted to be presented to work, and provided with a gate cooperating with the body; of means disposed in position to be engaged and substantially vertically actuated by the weight of the work by the work to which the body is applied to actuate the gate to move the same in a closing direction; latch means being further provided for holding the gate in closing position.

4. In an elevator of the character disclosed, a body adapted to be presented to work, and provided with a gate cooperating with the body; of means disposed in position to be engaged and substantially vertically actuated by the weight of the work by the work to which the body is applied to actuate the gate to move the same in a closing direction; said means for actuating the gate serving to retain the same in closing position; latch means being further provided to retain the gate in closing position.

5. In an elevator of the character disclosed, a body adapted to be presented to work, and provided with a gate cooperating with the body; of means disposed in position to be engaged and substantially vertically actuated by the weight of the work by the work to which the body is applied to actuate the gate to move the same in a closing direction; said means comprising cooperating cam and plunger members respectively associated with the body and the gate.

6. In an elevator of the character disclosed, a body adapted to be presented to work, and provided with a gate cooperating with the body; of means disposed in position to be engaged by the work to which the body is applied to actuate the gate to move the same in a closing direction; said means comprising cooperating cam and plunger members respectively associated with the body and the gate; said gate being hingedly connected with said body, and said cam member having a working surface lying in a curved inclined path partly circumscribing the axis of such hinged connection.

7. In an elevator of the character disclosed, a body adapted to be presented to work, and provided with a gate cooperating with the body; of means disposed in position to be engaged by the work to which the body is applied to actuate the gate to move

the same in a closing direction; said means comprising cooperating cam and plunger members respectively associated with the body and the gate; said gate being hingedly connected with said body, and said cam member having a working surface lying in a curved inclined path partly circumscribing the axis of such hinged connection; said plunger having a portion normally rising above the upper surface of the body, and accommodated in a chamber in the body.

8. In an elevator of the character disclosed, a body adapted to be presented to work, and provided with a gate cooperating with the body; of means disposed in position to be engaged by the work to which the body is applied to actuate the gate to move the same in a closing direction; said means comprising cooperating cam and plunger members respectively associated with the body and the gate; said gate being hingedly connected with said body, and said cam member having a working surface lying in a curved inclined path partly circumscribing the axis of such hinged connection; said plunger having a portion normally rising above the upper surface of the body, and accommodated in a chamber in the body; resilient means being provided urging the plunger into elevated position, whereby the gate may be free to move in an opening direction.

9. In an elevator of the character disclosed, a body adapted to be presented to work, and provided with a gate cooperating with the body; of means disposed in position to be engaged and substantially vertically actuated by the weight of the work by the work to which the body is applied to actuate the gate to move the same.

10. In an elevator of the character described, a body adapted to be presented to work and provided with a gate cooperating with said body, and engaging means on said gate and body whereby the weight of the work actuates the gate into closed position.

11. In an elevator of the character described a body adapted to receive work, a gate cooperating with said body, and means operated by the weight of the work adapted to actuate said gate into closed position.

12. In an elevator of the character described a body, a gate cooperating with said body, said body being formed to receive work when said gate is in open position, and cooperating means on said body and gate actuated by the weight of said work to actuate said gate into closed position.

In testimony whereof, I have signed my name to this specification.

HENRY M. PAULSEN.
